UNITED STATES PATENT OFFICE.

CHARLES F. BISHOP, OF LESTERSHIRE, NEW YORK.

DRIP-PAN.

1,034,340.

Specification of Letters Patent. Patented July 30, 1912.

Application filed June 12, 1911. Serial No. 632,813.

To all whom it may concern:

Be it known that I, CHARLES F. BISHOP, citizen of the United States, residing at Lestershire, in the county of Broome and State of New York, have invented certain new and useful Improvements in Drip-Pans, of which the following is a specification.

This invention relates to drip pans for use in connection with refrigerators employed in dwellings and the like where a portable drainage device is necessary for catching the dripping water from the ice.

The invention has for an object to provide a drip pan with a tube to carry off the water, a screen to catch the slime carried from the refrigerator with the water and prevent it from entering the tube.

Another object of this invention is to provide the inner end of the tube with a protecting screen cap, and to provide the drip pan with a screen disk above the cap to insure the stoppage of slime, the screen disk being detachable so that it can be renewed or taken from the receptacle and cleansed.

A further object of this invention is to provide a screen disk with an imperforate drip plate at its central portion upon which the water from the refrigerator is adapted to drop so that the particles of foreign substances carried in the water will not be forced through the screen disk by the pressure of the dripping water.

Other objects and advantages will be hereinafter referred to and more particularly pointed out in the claims.

For a full understanding of the invention, reference is to be had to the following description and accompanying drawing in which:

Figure 1 is a side elevation of the drip pan applied to a refrigerator; Fig. 2 is an enlarged central and vertical section taken through the drip pan; and Fig. 3 is a perspective view of the device, showing the parts removed from one another.

Corresponding and like parts are referred to in the following description and indicated in all the views of the drawing by the same reference characters.

Referring to the drawing, 10 designates a preferably cylindrical receptacle adapted to stand beneath the refrigerator and receive the dripping water from the feed pipe 11. The receptacle 10 is provided with a

fixed bottom 12 spaced above its lower edge

and having a laterally extending pipe 13 communicating through its central portion. The pipe 13 projects through the side of the receptacle 10 and carries one end of a coupling 14. The coupling 14 connects a length of preferably copper pipe 15 to the pipe 13, the pipe 15 being adapted to convey the water from the receptacle to any desired point of discharge. The bottom 12 slopes down to its central portion to insure the flow of the water to the pipe 13 and carries a screen cap 16 over the entrance to the pipe 13.

Fitted in the upper end of the receptacle 10 is an annular frame 17 provided with an outstanding annular bead 18 engaging the upper edge of the receptacle to limit the downward movement of the frame. The lower end of the frame 17 is closed by a disk screen 19 having its edge secured to the lower edge of the frame. An imperforate drip plate 20 engages diametrically across the frame 17 and forms the central portion of the disk, the disk thereby being divided into two sections having their inner opposite edges suitably secured to the opposite edges of the drip plate 20. A laterally extending handle 21 is carried upon the frame 17 to admit of the removal of the frame when it is desired to cleanse the disk.

In use, the water in the refrigerator drops from the pipe 11 on to the central portion of the drip plate 20. The water spreads over the drip plate and filters through the screen 19 into the receptacle 10. The foreign substances usually carried off from the refrigerator in the water are held upon the disk screen 19 from falling into the receptacle, particularly since there is no force upon the water to force the particles through the screen. The water drops directly upon the drip plate 20 which is imperforate and flows laterally therefrom over the disk sections. The water disposed in the receptacle 10 moves by gravity toward the central portion of the bottom 12 and passes through the cap 16 and into the pipe 13. The water is conveyed through the pipe 15 to any suitable point of discharge.

When the disk screen 19 becomes clogged it can be readily removed by the handle 21 and be cleansed, the dripping water filtering through the cap 16, while the screen disk 19 is removed. When the device is assembled the water filters through the disk screen 19

and also the cap 16 so as to insure the stoppage of foreign substances carried by the water.

What I claim is:

- 5 1. A drip pan comprising a receptacle, a raised bottom in the receptacle, a drainage pipe communicating with the central portion of the bottom to carry water from the receptacle, a screen cap carried upon the bottom covering the open end of the drainage pipe, a detachable frame fitted in the upper end of the receptacle, a screen disk carried by the frame, and an imperforate drip plate arranged centrally within the frame to receive the dripping water from the refrigerator.
- 10 2. A drip device for refrigerators comprising a receptacle, a drip plate carried across the upper end of the receptacle to receive dripping water from the refrigerator, screens at opposite sides of the drip plate to filter the water flowing from the drip plate, a screen cap carried in the bottom of the receptacle, and a drainage pipe opening into the screen cap to carry off the water from the receptacle.
- 15
- 20
- 25

3. A drip pan comprising a receptacle, a screen closing the upper end of the receptacle, a drip plate arranged centrally in the receptacle to receive the impact of the dripping water, a drainage pipe communicating with the receptacle, and a screen cap closing the inner end of the drainage pipe.

4. A drip pan comprising a receptacle, a bottom arranged in the receptacle and inclining toward its central portion, a drainage pipe communicating with the central portion of the bottom, a screen cap closing the inner end of the drip pipe, a frame fitted in the upper end of the receptacle, a handle laterally projecting from the frame to remove the same from the receptacle, a screen disk carried across the lower edge of the frame, and a drip plate carried by the frame for receiving the impact of the water dropped into the receptacle.

In testimony whereof, I affix my signature in presence of two witnesses.

CHARLES F. BISHOP. [L.S.]
